SPOON OR SIMILAR ARTICLE

Grosvenor N. Allen, Oneida, Mary Parker Fleming, Fulton, and Lloyd E. Ressegger, Oneida, N. Y., assignors to Oneida Ltd., Oneida, N. Y., a corporation of New York

Application April 15, 1949, Serial No. 2,016

Term of patent 14 years

(Cl. D54—12)

To all whom it may concern:

Be it known that we, Grosvenor N. Allen, Mary Parker Fleming, and Lloyd E. Ressegger, citizens of the United States, residing, respectively, at Oneida, county of Madison, and State of New York, at Fulton, county of Oswego, and State of New York, at Oneida, county of Madison, and State of New York, have invented a new, original, and ornamental Design for a Spoon or Similar Article, of which the following is a specification, reference being had to the accompanying drawing, forming a part thereof, in which

Figure 1 is a front view of a spoon showing our new design;

Figures 2, 3 and 4 are sections taken on the respective lines 2—2, 3—3, 4—4 of Figure 1; and

Figure 5 is an enlarged fragmentary face view of the handle of the spoon for the purpose of bringing out more clearly the details of ornamentation.

The essential features of our design for a spoon or similar article reside in the configuration of the handle in combination with the particular type of ornamentation as applied thereto.

We claim:

The ornamental design for a spoon or similar article, substantially as shown and described.

GROSVENOR N. ALLEN.
MARY PARKER FLEMING.
